OMNIDIRECTIONAL LAMP

Edward Wilfrid Thomas, Chamblee, Ga., assignor to
Unitron International Systems, Inc., Atlanta, Ga.

Filed July 29, 1974, Ser. No. 492,437

Term of patent 14 years

Int. Cl. D10—06; D26—02

U.S. Cl. D48—24 R

FIG. 1

FIG. 2

FIG. 3

FIG. 1 is a perspective view of an omnidirectional lamp showing my new design; FIG. 2 is a top plan view thereof; and FIG. 3 is a side elevational view thereof.

I claim:

The ornamental design for an omnidirectional lamp, as shown and described.
